UNITED STATES PATENT OFFICE

128,477

DESIGN FOR A POWER SHOVEL CAB

Lawrence E. Blazey, Cleveland, Ohio, assignor to
The Byers Machine Company, Ravenna, Ohio,
a corporation of Ohio

Application May 14, 1941, Serial No. 100,939

Term of patent 14 years

To all whom it may concern:

Be it known that I, Lawrence E. Blazey, a citizen of the United States and a resident of Cleveland, Cuyahoga County, Ohio, have invented a new, original, and ornamental Design for a Power Shovel Cab, of which the following is a specification, reference being had to the accompanying drawings forming a part thereof.

In the drawings:

Fig. 1 is a top plan view of a power shovel cab showing my new design;

Fig. 2 is a left side elevational view;
Fig. 3 is a right side elevational view;
Fig. 4 is a front elevational view; and
Fig. 5 is a rear elevational view;
I claim:
The ornamental design for a power shovel cab,
as shown.

LAWRENCE E. BLAZEY.
